UNITED STATES PATENT OFFICE.

ALBERT MARTINDELL, OF TRENTON, NEW JERSEY.

COIN-OPERATED AMUSEMENT DEVICE.

SPECIFICATION forming part of Letters Patent No. 770,299, dated September 20, 1904.

Application filed November 21, 1903. Serial No. 182,132. (No model.)

To all whom it may concern:

Be it known that I, ALBERT MARTINDELL, a citizen of the United States, residing at Trenton, in the county of Mercer and State of New Jersey, have invented a new and useful Improvement in Coin-Operated Amusement Devices, of which the following is a specification.

My invention relates to that class of devices in which automatons are operated by mechanical means, the said means being set in motion by the insertion of a coin into a proper coin-chute.

The object of my invention is to improve the means for operating the figures, to operate said means by a weight, to provide a lever for moving the weight into the proper position to work the mechanism, to lock the mechanism against movement while the weight is being raised to its operative position, and to lock the lever against movement until the proper coin has been inserted into the coin-chute.

My invention consists in carrying out these various objects by means of the novel features of construction and combination of parts hereinafter described, particularly pointed out in the claims, and shown in the accompanying drawings, in which—

Figure 1 is a perspective view of my device. Fig. 2 is a vertical section through the device. Fig. 3 is a perspective view showing the lever partly in section and the locking mechanism in locking position. Fig. 4 is a side elevation of the parts shown in Fig. 3, the lever being shown in cross-section and the locking parts being disengaged from the lever. Fig. 5 is a plan view of the frame carrying the winding-drums and gear-train.

Fig. 6 is a detail view of the pawl and ratchet. In constructing my device I employ a rectangular box A, cut out at one end, on one side, and at the top, and glass panels A' are fitted in the cut-out portions, which may be of any size and shape desired. The box is provided with a false bottom A², which stops short of a rear corner of the box, whereby a well A³ is provided. A coin-drawer A⁴ is arranged below the false bottom and is provided with a lock A⁵ of any desired make.

A lever B is pivotally connected at its inner end to a bracket B', carried on the inner face of the rear wall of the box adjacent the well A³, and the outer end portion of the lever B projects through the front wall of the box, 55 the lever working vertically in an elongated slot A⁷, formed in the said front wall. Within the box adjacent and parallel to the slot B' is arranged a vertical coin-chute C. This chute is notched or cut away on one side, as shown 60 at C', and the chute below the cut-out portion C' is slightly offset with reference to that portion of the chute above the cut-out portion, and the non-cut-out wall of the chute is slightly curved, as shown at C², whereby the 65 coin is directed in its fall parallel to the front wall of the casing and guided into the offset portion.

A metal plate D is secured to the front wall parallel with the coin-chute and at a right angle to the lever B, and to this plate is pivotally connected a locking-bar E, the bar being pivoted intermediate its ends. In the lever B is formed an aperture B², and the bar E has formed on it adjacent its upper end a 75 keeper adapted to engage the aperture of the lever and lock the same against movement, this keeper or projection E' working toward and away from the lever as the bar swings on its pivot-point. 80

Below the pivotal point the locking-bar is reduced in width and arranged at a slight angle with reference to the upper part of the bar, the angle being such that when the keeper E' is in engagement with the aperture B² of 85 the lever the lower portion of the bar will project into the cut-out portion C' of the coin-chute and partly restrict the passage.

A cam member is pivotally connected to the plate D, and this member F has a cam edge 90 F', adapted to be engaged by the lever B. The cam is guided and limited in its movements by screw or bolt F², extending through a curved slot F³, formed transversely in the cam-body. The cam has a laterally-extending arm F⁴, which is pivotally connected to the reduced lower portion of the locking-bar E. 95

Arranged in the upper portion of the box above the lever is a frame G. This frame carries a plurality of stub-shafts H, H', and H², 100

H and H² projecting laterally beyond the frame. The outer end of the shaft H carries a drum J and also a drum J', arranged within the frame and larger than the drum J. A gear-wheel K is also arranged loosely on the shaft H and carries a spring-pressed pawl K', engaging a ratchet K², arranged rigidly on the shaft between the drum J' and the gear K. This pawl and ratchet are so arranged that when the belt or cable L is wound up on the drum J' the pawl will slip and the gear K remain stationary; but when the cable unwinds the pawl is engaged by the ratchet-teeth and the gear-wheel K will be rotated. The stub-shaft H' carries a pinion K³, engaged by the gear-wheel K, and a gear-wheel K⁴ in engagement with a pinion K⁵ on the shaft H². The outer end of the shaft H² terminates in a cranked handle portion M, to which is attached a cord M', the cord dividing adjacent its lower end, each branch being attached to an automaton M'.

A weight L' is attached to the lower end of the cable L and works in the well A³. A cable N winds on the drum J and is secured at one end to the lever B. A brake-arm O is pivoted at one end to a bracket O' and has its opposite end bent to engage the teeth of the gear-wheel K⁴. A arm P, carried by the lever, is adapted to engage the brake-arm O when the lever is in its normal position and hold the bent end out of engagement with the gear-wheel K⁴. A coin-slot A⁶ is formed in the top of the box in alinement with the coin-chute C. The parts are normally in the position shown in Figs. 1, 2; and 3.

The operation of my device is as follows: When a coin is dropped into the chute C, no obstacle is offered to its downward passage until it reaches the offset or cut-out portion of the chute, where it contacts with the curved wall C² and is thrown with some force against the lower end of the locking-bar, which is projected into the path of the coin. The weight of the coin forces this end outward and the upper end is drawn inward, disengaging the keeper E' from the aperture in the lever B, permitting the lever to fall. The outward movement of the lower portion of the bar E will also throw outward the cam member F, and the lever in its fall will strike the edge F', force the cam member inward, and through the arm F' will return the locking-bar to its normal position. The downward movement of the lever unwinds the cable N, rotating the drum J, shaft H, and drum J', winding the cable L on the latter and drawing up the weight L', the gear-train being locked by reason of the brake-arm O having fallen into engagement with the gear-wheel K⁴ on the fall of the lever and withdrawal of the arm P. The person depositing the coin in the chute then lifts the lever B to its normal position, and the keeper E' being bevelled on the under side it will again come into engagement with the aperture B² and lock the le-

ver against further movement until another coin has been deposited in the chute. As the lever is returned to its normal position it lifts the brake-arm through medium of the arm P out of engagement with the gear-wheel K⁴, and the fall of the weight L', which cannot descend until the lever is lifted, rotates the drum J' and shaft H in such direction that the gear-wheel K is rotated through the pawl and ratchet, and the crank-arm or handle M is rotated through rotation of the train of gears and a reciprocal movement imparted to the cord M', which causes the automaton to display life-like movements resembling a boxing match, dancers, or such other representations as it may be desired to display.

Any of the usual well-known means for preventing working of the device by coins having strings attached to them may be employed in connection with this device. In Fig. 1 I have shown a vertical plate Q, which is intended simply to hide from view the construction of the locking mechanism. This plate may be omitted, if desired. It will also be understood that glass panels may be arranged in the casing or box-frame at any points desired and on all four sides.

Having thus fully described my invention, what I claim as new, and desire to secure by Letters Patent, is—

1. In a coin-controlled apparatus, a pivoted, apertured lever adapted to fall by gravity, a locking-bar pivoted intermediate its ends and having a keeper adjacent its upper end adapted to engage the aperture of the lever, a coin-chute adapted to be partially closed by the lower end of the locking-bar, a movable cam member pivotally arranged in the path of the lever, and an arm connected at one end to the cam and at the opposite end pivoted to the locking-bar.

2. In a coin-controlled apparatus, a casing vertically slotted, a coin-chute arranged adjacent the slot said chute being cut out on the side adjacent the slot, a lever pivoted in the casing and extending outwardly through the slot, a locking-bar pivoted intermediate its ends to the side of the casing, a keeper on said locking-bar adapted to engage the lever, the lower end of the locking-bar extending into the cut-out portion of the coin-chute, a cam member pivoted to the casing and having a cam-face normally extending across the slot in the casing and in the path of the lever, the said cam having a curved slot in its body portion, a stop-bolt arranged on the inner face of the casing and projecting into the slot in the cam member and adapted to limit the movement of the cam, and an arm carried by the cam and connected to the locking-bar.

3. A coin-controlled apparatus comprising a casing slotted vertically, a lever pivoted within the casing and extending through and working in the said slot, a vertically-arranged, continuous coin-chute arranged adjacent the

said slot, the said chute having a cut-out portion on the side facing the vertical slot in the casing and the opposite wall of the chute being curved toward the cut-out portion and adapted to direct a coin toward the said cut-out portion, the chute below the cut-out portion being slightly offset with respect to the portion of the chute above the cut-out portion, and a locking-bar pivoted to the casing 5 between the vertical slot and the coin-chute,

the upper portion of the said locking-bar being adapted to engage the lever and the lower portion being adapted to project into the cut-out portion of the coin-chute, as and for the purpose set forth.

ALBERT MARTINDELL.
